UNITED STATES PATENT OFFICE.

VICTOR H. JENNINGS, OF WORCESTER, MASSACHUSETTS, ASSIGNOR TO MILLS WOVEN
CARTRIDGE BELT COMPANY, OF WORCESTER, MASSACHUSETTS, A CORPORATION OF
MASSACHUSETTS.

CARTRIDGE BELT OR CARRIER.

1,139,874.

Specification of Letters Patent. Patented May 18, 1915.

Application filed May 10, 1911. Serial No. 626,188.

To all whom it may concern:

Be it known that I, VICTOR H. JENNINGS, a subject of the King of Great Britain, residing at Worcester, in the county of Worcester, State of Massachusetts, have invented a certain new and useful Improvement in Cartridge Belts or Carriers, of which the following is a specification, reference being had therein to the accompanying drawings.

10 The invention has relation to cartridge-belts and carriers, and other like articles of woven material having pockets furnished with covers or flaps.

More particularly, it relates to those in which the cover or flap of a pocket consists of a separate piece attached at one end thereof to the back wall of the pocket.

A general aim of the invention is to simplify the operations in assembling covers or flaps in connection with a pocket or series of pockets and in attaching them in place, reduce the number of operations, and enable the work of assembling and that of attaching to be performed more conveniently and rapidly.

The invention is illustrated in the accompanying drawings, in which,—

Figure 1 shows a portion of a cartridge-belt or carrier embodying the invention. Fig. 2 is a top view of the portion of belt or carrier that is shown in Fig. 1, the covers or flaps being omitted. Fig. 3 shows one of the covers or flaps of Fig. 1 separately. Fig. 4 is a view in vertical section in the plane indicated by the dotted line 4—4 of Fig. 1. Fig. 5 shows a portion of a cartridge-belt or carrier embodying the invention. Fig. 6 shows a portion of a cartridge-belt or carrier, but with differences in construction. Fig. 7 shows one of the covers or flaps of Fig. 6 separately.

In the various figures of the drawings the pockets are marked A, A, and the portions of web with which they alternate are marked B, B. The respective covers or flaps are marked C in Figs. 1, 3 and 4, C' in Fig. 5, and C² in Figs. 6 and 7. In the case of each of the illustrated constructions the attaching portion of a cover or flap, *i. e.*, the lower end thereof, occupies a housing slit a. Such slit is shown located at the top of the belt or carrier, which is preferable, although the location may be varied in practice. The two thicknesses d, d, of material between which the housing slit exists are shown as integral

portions of the back D, Fig. 4, of the belt, which is preferable but not invariable in practice. In Figs. 1 to 5 the housing slit a is continuous and extends in both directions beyond the sides of the pockets of a belt or carrier. In Fig. 6 the continuity of the slit is interrupted by joining the two plies together in the weaving, as at d², at middle distance between successive pockets, the openings being longer than the width of the pockets.

In assembling the parts, the attaching portion of a cover or flap is pushed endwise into the housing slit in proper relation with a pocket, until the extremity of such portion reaches the bottom of the slit. This fixes the extent to which the cover or flap can be entered into the slit. To guide in setting the cover or flap widthwise in relation to the pocket, indicators may if desired be provided in connection with the cover or flap and the back wall of the pocket. These indicators may be provided by the process of weaving and may vary in character, number, and arrangement. The drawings represent each cover or flap as woven with a characteristic line c extending lengthwise thereof, at midwidth thereof, and the back wall of each pocket as woven with a corresponding line d' at midwidth thereof. The two lines c, d', register with each other when the cover or flap occupies the required position widthwise with relation to the pocket, and any departure from such position will be indicated by the failure of the lines to register properly. Thereby correct setting of the cover or flap so that the marginal portions thereof shall project equally far at the opposite sides of the pocket is provided for. The indicating line c of the cover or flap may be produced in the weaving through the employment of one or more warp-threads of distinguishing size, material, or color; or of a single warp-thread in case the other warp-threads are disposed in pairs in the weaving, or of more than two warp-threads side by side woven as one; or by change in the character of the weaving, along such line. The indicating line d' of the back wall of the pocket may be produced by a change in character of the weaving at such line, or by dropping out a pick of weft, or by putting in a double pick, or a pick or two of a different color. Or one or more threads of different size, material, or color,

having been carried along as part of the warp, but so employed as not to appear at the front of the fabric, may be thrown to the face for one or more picks at the predetermined point.

As shown in Figs. 1, 4, 5 and 6 both of the thicknesses or plies between which the housing slit exists extend or project above the tops of the pockets sufficiently to receive 10 the line of stitches E by which the said thicknesses or plies and the cover or flap inserted between them are all fastened together. This feature enables all the covers or flaps of a series of pockets to be secured 15 in place in one operation by a straight-away line of stitches along the projecting upper marginal portion of the belt or carrier, without the inconvenience or difficulty and loss of speed which would be incident to 20 pushing the loose front wall of each pocket in succession back out of the way of the stitching devices, and stitching across the top portion of one pocket at a time, between the closed sides of the pocket. An important saving in time and labor is thereby 25 effected. The like advantages and saving are secured by the invention in cases in which other fastenings, such for instance as staples or rivets, are employed in lieu of 30 the stitches E or in addition thereto, as I intend in some cases in practice. The upward extension of the back wall also facilitates the application of the rivets F, F, which are usually employed to assist in fas- 35 tening the flaps or covers to the said wall, inasmuch as the said rivets may be placed higher up than heretofore, which is easier because of less interference of the front portions of the pockets with the riveting 40 devices.

In Figs. 5, 6 and 7 of the drawings the covers or flaps are so much wider than the pockets that the proximate side-margins of adjoining covers or flaps overlap with each 45 other to a material extent so long as the belt or carrier is in a straight or extended condition. When, however, the belt or carrier is bent or curved for use, the pockets are caused to diverge in different radial or 50 substantially radial directions and thereby

are spread apart so that the said side-margins are drawn away from each other and no longer overlap. Fig. 5 illustrates covers or flaps with their attaching portions in flat or straight condition inserted in a continuous housing slit, in which latter, as well as externally thereto, the side-margins of the covers or flaps are overlapped with each other. Figs. 6 and 7 illustrate covers or flaps with their attaching portions tapered 60 by having the lower corners thereof folded or turned inward. In this construction the side-margins of the covers or flaps do not overlap within the housing slit, and the opposite thicknesses or plies d, d, may be 65 joined together in the weaving, as at d², between proximate pockets.

What is claimed as the invention is:

1. A pocketed carrier woven with a pocket and having one of its web-portions 70 for a portion of its depth in divided plies with a junction located above the bottom of the said pocket and with portions of said plies projecting above the top of the opposite pocket-wall, and having combined with 75 such web-portions a cover-flap having its attaching end inserted between said plies, and fastening means engaging with the inserted portion above said top and attaching the cover-flap to the said web-portion. 80

2. A pocketed carrier woven with a series of pockets and having one of the web-portions of the respective pockets for a portion of the pocket-depth in divided plies with a junction located above the bottom of the 85 pocket, and with portions of said plies projecting above the tops of the opposite pocket-walls, and having combined with the said web-portions cover-flap material having the attaching portion thereof inserted 90 between said plies, and fastening means engaging with the inserted portion above said tops and attaching the cover-flap to the said web-portion.

In testimony whereof I affix my signature 95 in presence of two witnesses.

VICTOR H. JENNINGS.
